ALEXANDER BROOKS, OF WAVERLY, NEW YORK.

Letters Patent No. 65,870, dated June 18, 1867.

IMPROVED WASHING MACHINE.

The Schedule referred to in these Letters Patent and making part of the same.

TO ALL WHOM IT MAY CONCERN:

Be it known that I, ALEXANDER BROOKS, of Waverly, in the county of Tioga, and State of New York, have invented a new and improved Washing Machine; and I do hereby declare that the following is a full, clear, and exact description thereof, which will enable others skilled in the art to make and use the same, reference being had to the accompanying drawings, forming part of this specification, in which—

Figure 1 is a vertical longitudinal section of my improved washing machine taken through the line xx , fig. 2.

Figure 2 is a vertical cross-section of the same, taken through the line yy , fig. 1.

Similar letters of reference indicate like parts.

My invention has for its object to furnish an improved washing machine, so constructed and arranged as to wash the clothes rapidly, thoroughly, and conveniently, and without injury to the fabric; and it consists in the combination of circular slats, circular plates, and breast-beams with each other and with the box of the machine, in forming a box at one end of the machine for the attachment of a wringer; and in the combination of the pivoted hammer and weight with each other, and with the box of the machine; the whole being constructed and arranged as hereinafter more fully described.

A is the box of the machine, the bottom a^1 of which is made flat, the sides a^2 vertical, and the ends a^3 inclined, as shown in figs. 1 and 2. B are circular slats, placed in the bottom of the box A, the spaces between and beneath them acting as reservoirs to contain the water or suds, so that so great a depth of water above said slats will not be necessary to thoroughly wet the clothes being washed. C are circular zinc plates, extending from the ends of the circular slats B to the breast-beams D, at each end of the box A, the plates C being attached to blocks or ribs so that their surfaces may be in the same circle with the circular slats or ribs B, as shown in fig. 1. D are the breast-beams, secured in the ends of the box A, and so arranged that their under sides may be nearly in a line with the pivoting point of the hammer or beater E. The hammer or beater E is made heavy, and its lower side or part is slotted, as shown in fig. 2, so that it may pass more easily through the water or suds, and need not carry so much water up with the clothes. The ends of the hammer or beater E are attached to the arms F, by means of which it is pivoted to the sides a^2 of the machine or to a shaft, G, attached to said sides. The arms F extend above the pivoting point, and have a weight, H, attached to them at about the same distance from the pivoting point as the hammer E. The weight H should be about three-fourths the weight of the said hammer E. The hammer or beater is operated by a handle or lever, I, so connected to the upper side of the weight H that it may be used both to push and pull, so that the hammer or beater may make its stroke in both directions. J is a box, formed in one end of the box A, so that a wringer may be conveniently attached to said box, and may remain there while the machine is being operated. The box J is connected to the interior of the box A by channels, so that the water wrung from the clothes may flow back into the said box. K are movable covers, placed upon the machine to prevent the water from splashing out while the hammer is being operated.

In using the machine a sufficient quantity of water and soap is put into the box A, a part of the clothes are then put in upon each side of the beater E, which is then operated, carrying the clothes with it up the circular plates C and beating out the water and dirt against the breast-beams D. As the hammer swings back the clothes slide down the circular plates C, and when they reach and come in contact with the circular slats or ribs B, they are partially turned over so that a different part of them may be operated upon at each stroke of said hammer. The ends of the circular slats B, where they meet the plates C, may be made a little full so as to facilitate the partial turning over of the clothes.

What I claim as new, and desire to secure by Letters Patent, is—

1. The combination of the circular slats or ribs B, circular plates C, and breast-beams D, with each other and with the box A of the machine, substantially as herein shown and described and for the purpose set forth.

2. The pivoted hammer E, and weight H, constructed, arranged, and operated substantially as herein shown and described, in combination with the box A, as and for the purpose set forth.

ALEXANDER BROOKS.
